UNITED STATES PATENT OFFICE.

BENJAMIN F. JACKSON, OF VERSAILLES, INDIANA.

SELF-PROPELLED BOAT.

1,304,318.

Specification of Letters Patent. Patented May 20, 1919.

Application filed September 27, 1918. Serial No. 255,907.

To all whom it may concern:

Be it known that I, BENJAMIN F. JACKSON, a citizen of the United States, residing in the city of Versailles and State of Indiana, have invented new and useful Improvements in Self-Propelling Boats, of which the following is a specification, reference being had to the accompanying drawings.

This invention pertains to self-propelling boats, and has for its object the production of a device of this character which will be automatically operated through the force and vibration of the waves in such a manner as to propel the boat across the water.

15 A further object is to produce this device in a simple, practical and efficient form.

With these objects in view, attention is called to the accompanying drawings, wherein—

20 Figure 1 represents a longitudinal elevation of a boat floating in the water and properly equipped with this apparatus;

Fig. 2 is a plan view of the propelling apparatus;

25 Fig. 3 is an end view of the propelling apparatus and a portion of the boat.

Fig. 4, a detail of a set of the propeller blades, showing same in open position and ready to move forwardly through the water;

30 Fig. 5, a similar view, showing the blades closed and ready to press backwardly against the water in order to propel the boat forward;

Fig. 6, a detail of the air piston or shock absorber system located between the boat sections in order to absorb the shock resulting from the oscillation of said sections.

Referring more particularly to the drawings, my invention consists of two buoyant boat sections 1 and 2 hinged together transversely and medially by means of suitable hinge members 3 and 4 located on opposite sides of the sections. These hinge members 3 and 4 are located, as shown, near the top 45 of the buoyant sections, the result of which arrangement is that said sections in floating upon the water are acted upon by the waves to cause a relative oscillating or reciprocating motion between said sections, and so 50 that the ends 5 and 6 of said sections oscillate toward and from each other, moving upon the pivotal links 3 and 4. In order to prevent the sudden shock which would otherwise result between the abutting ends 55 5 and 6, suitable shock absorbers as 7 and 8

are located respectively below and above the pivotal links 3 and 4.

Upon the bottom of the boat supported by suitable stays and braces as 9 and 10, and located one toward each side of the rear section 2, are the propelling members 11 and 12. Each propelling member is made up of longitudinal and parallel bars as 13, 14, 15 and 16, pivotally connected at the points 17, 18, 19, 20, 21, 22, 23 and 24 to the horizontally disposed lever arms 25, 26, 27 and 28. Said lever arms are in turn pivotally connected at the points 29, 30, 31 and 32 to the ends of the braces 9. Swingly mounted from the bars 13 and 14 upon one side, and 15 and 16 upon the other side, extend the horizontally disposed outstanding propeller arms 33 and 34. These arms are pivotally connected to the inner bars 13 and 15 at the points 35 and 36, and pass loosely through the outer bars 14 and 16 through the slots 37 and 38. This arrangement and mounting enables the bars 13 and 14 on one side, and 15 and 16 upon the other side to reciprocate back and forth upon the pivotal points 29, 30, 31 and 32, and so reciprocating, to cause the propeller arms 33 and 34 to likewise move forward and backward alternately. Upon each set of extended propeller arms 33 and 34 are mounted a series of shutter-like propeller blades 39. These propeller blades are disposed vertically, and are hingedly mounted upon the propeller arms 33 and 34 from their forward edges, as at 41, and in such manner that as the propeller arms advance forwardly through the water, the propeller blades will be automatically forced open, so as to pass easily through the water, and contrariwise when the propeller blades reach their forwardmost position and start to move backwardly, said blades will by reason of the pressure of the water automatically close, and thereby offer an unbroken propelling surface against the water, resulting in propelling the boat forwardly through the water.

Pivotedly attached to the forward levers 25 and 26 from the points 43 and 44 are the forwardly extending power transmission arms 45 and 46, and the forward ends of these arms are pivotally connected at the points 47 and 48 to the lugs 49 and 50 rigidly mounted upon the forward section 1 at points near the bottom and to either side thereof. By this arrangement, as the boat

sections float upon the water, successive waves passing thereunder result in a reciprocating or oscillating motion between the sections 1 and 2, whereby the power 5 transmission arms 45 and 46 are caused to reciprocate back and forth, and in turn, the propeller blades 39 and 40 are caused to open and move forwardly through the water, and then to close and move backwardly 10 against the water, as above stated, thereby causing the boat sections to move forwardly through the water. At the same time the shock absorbers 7 and 8 regulate the oscillations between the two sections and prevent 15 any abrupt shocks of contact.

The apparatus as described may be located directly upon the bottom of shallow draft boat sections. Where sections of deeper draft are employed, the apparatus 20 may be mounted upon either side of the section and far enough upwardly along the sides to enable the wave action to have the proper effect upon the apparatus.

While I have herein described a certain 25 specific manner and method of constructing the elements of my invention, it is understood that I may vary from the same in minor details, not departing from the spirit of my invention, so as best to construct a 30 practical device for the purpose intended, as defined in the appended claims.

What I claim to be new and patentable is:

1. A self propelling boat, comprising a plurality of boat sections connected for reciprocating motion; a frame mounted in connection with certain boat sections; a plurality of reciprocating propeller arms mounted in the frame; a plurality of propeller blades hinged to each of said propeller 40 arms and adapted to open for edgewise forward motion through the water and to close flatwise for reverse backward motion; and a plurality of power transmission arms connecting said propeller arms with certain 45 other boat sections so as to transmit the oscillating motion between the boat sections to said propeller arms.

2. A self propelling boat, comprising a plurality of boat sections connected for reciprocating motion; a frame mounted in 50

connection with certain boat sections; a plurality of reciprocating propeller arms mounted in the frames; a plurality of propeller blades hinged to each of said propeller arms and adapted to open for edgewise forward motion through the water and to close flatwise for reverse backward motion; a plurality of power transmission arms connecting said propeller arms with certain other boat sections so as to transmit the oscillating motion between the boat sections to said propeller arms; and means for neutralizing the shock between the different oscillating boat sections. 55

3. A self propelling boat, comprising a plurality of boat sections connected for reciprocating motion; a frame mounted in connection with certain boat sections; a plurality of reciprocating propeller arms mounted in the frame; a plurality of propeller blades hinged to each of said propeller arms and adapted to open for edgewise forward motion through the water and to close flatwise for reverse backward motion; a plurality of power transmission arms 70 connecting said propeller arms with certain other boat sections so as to transmit the oscillating motion between the boat sections to said propeller arms; and a plurality of shock absorbers mounted between the boat 75 sections so as to neutralize the shocks.

4. A self propelling boat, comprising two boat sections connected on a medial transverse line from their upper sides; a frame mounted from one boat section; a plurality of propeller arms pivotally mounted in the frame for lever-like reciprocating motion; a plurality of propeller blades hinged to each propeller arm so as to open for edgewise forward motion through the water 80 and to close flatwise or backward motion; power transmission arms connecting the inner ends of said propeller arms with the other boat section, so as to transmit the oscillating motion between the boat sections 85 to said propeller arms and blades.

BENJAMIN F. JACKSON.
